UNITED STATES PATENT OFFICE.

JOSEPH V. PETRELLI, OF NEW ROCHELLE, NEW YORK, ASSIGNOR TO TUTTLE & BAILEY MANUFACTURING COMPANY, OF NEW YORK, N. Y., A CORPORATION OF NEW YORK.

REGISTER.

Application filed April 14, 1926. Serial No. 101,880.

This invention relates to an improvement in registers, and has for its object the provision of an improved mounting for the shutter member so arranged that the parts can be readily and accurately adjusted to compensate for wear. The frictional surfaces of the pivot are made of dissimilar metals so chosen as to insure a smooth pivotal action and also to produce a thermostatic action to increase the frictional resistance of the pivot when the parts become heated thereby helping to maintain the shutter at the desired position when heat is issuing from the register.

15 While I have disclosed a preferred embodiment of the invention it will be clear that various changes and modifications can be made without departing from the true spirit and scope of the invention as herein-
20 after defined and claimed.

In the drawings:

Fig. 1 is a front elevation of a register embodying the invention;

Fig. 2 is a fragmentary section on line 25 2—2 of Fig. 1;

Fig. 3 is a rear elevation of the pivotal arrangement;

Fig. 4 is a section on line 4—4 of Fig. 3;

Fig. 5 is a detail view showing the pivot 30 pin.

Referring more particularly to the drawings, the grating member 10 is detachably fastened by screws 11 to the casing 12 adapted to be set into the heat duct. The 35 passage of heat from the heat duct through the register is controlled by the shutter member 13 which is pivotally mounted on the rear side of the grating member 10 in a manner now to be described.

40 A steel joint member 14 is riveted at its lower end to the shutter member 13 and carries integral ears 15 and 16. One end of member 14 projects through the grating member and is bent to form the operating lever 17. A steel joint member 18 is riveted 45 to the rear side of the grating member and carries an integral strap bent to form a barrel portion 19 and a projecting tongue 20. In assembling the parts the barrel portion is inserted between the ears 15 and 16, and a brass pivot pin 21 is inserted through 50 openings in the ears coinciding with the opening in the barrel portion 19. The opening in ear 16 is hexagonal to receive a hexagonal shoulder 22 formed on the pivot pin

to hold the pin against rotation in the ears 15 and 16. After the joint is assembled the pin 21 is riveted over as at 23 to maintain the parts together.

An adjusting screw 24 is set into an opening 25 in the grating member and passing through an opening 26 in the joint member 18 is screw threaded into the tongue 20 at 27.

It will be evident that by turning down 65 the adjusting screw 24 the strap member 19 will be tightened upon the pivot pin 21. When the parts are in proper relation the shutter may be moved by lever 17 to any desired angular position to control the 70 amount of heat issuing from the register. Since the friction is produced by steel moving over brass the pivotal movement will be smooth and quiet. Brass has a higher coefficient of expansion than steel and hence 75 as the parts become heated the brass will expand faster than the steel to thereby increase the frictional resistance of the pivot and insure the maintenance of the shutter at the desired angular position while heat 80 is issuing from the register. It should also be noted that the adjustable strap member completely surrounds the pivot pin and forms a very efficient adjusting means.

I claim:

1. A register comprising a casing, a shutter, a pair of up-standing ears carried by the shutter near the center of one edge of the shutter, a pivot pin mounted in the ears, and an adjustable strap carried by the casing 90 and surrounding the pivot pin to adjustably support the shutter.

2. In a register, a grating secured to a casing, a shutter, a joint member fastened to the shutter and having integral ears, a pivot pin non-rotatively mounted in said ears, and an adjustable strap carried by the grating and surrounding the pivot pin. 95

3. In a register, a grating secured to a casing, a shutter, a joint member fastened to the shutter and carrying a pivot pin of relatively expandable material, and a strap of less expandable material carried by the grating and surrounding the pivot pin. 100

4. In a register, a grating secured to a casing, a joint member fastened to the grating and having a strap bent to form a barrel, a shutter, a joint member secured to the shutter and having integral ears, a pivot pin passing through the barrel and non-rotat- 105 110

tively mounted in the ears, and means for adjusting the frictional contact between the barrel and the pivot pin.

5. In a register, a grating secured to a casing, a joint member fastened to the grating and having a strap bent to form a barrel and a projecting tongue, a shutter, a second joint member secured to the shutter and having integral ears, a pivot pin passing through the barrel and non-rotatively mounted in the ears, and an adjusting screw passing through the first-named joint member and threaded into the tongue.

6. In a register, a grating detachably secured to a casing, a joint member of material having a relatively low coefficient of ex-

pansion fastened to the grating and having a strap bent to form a barrel and a projecting tongue, a shutter, a second joint member secured to the shutter and having integral ears, a pivot pin of material having a higher coefficient of expansion than the joint member passing through the barrel and non-rotatively mounted in the ears, an adjusting screw passing through the first-named joint member and threaded into the tongue, said adjusting screw being accessible from the exterior of the register, and an operating lever formed integral with the second joint member.

In testimony whereof I affix my signature.

JOSEPH V. PETRELLI.
